UNITED STATES PATENT OFFICE

LEON W. CHASE, OF LINCOLN, NEBRASKA, ASSIGNOR TO CHASE PLOW COMPANY, A CORPORATION OF NEBRASKA

LAND MARKER

Application filed November 17, 1927. Serial No. 233,929.

My invention relates to landmarks and its primary object is the provision of landmarker structure which will be automatically raised and lowered whenever the plows are 5 raised and lowered.

Another of my objects is the provision of adjustable features whereby the marker arm may be adjustably supported in accordance with the depth of plowing.

10 Another of my objects is to provide a marker structure which is adapted for use on listers so as to mark the new row parallel to a previous furrow.

Still another of my objects is the provision 15 of a marker structure of extreme simplicity and which is operable without requiring any attention other than the original adjustment.

Having in view these objects and others which will be pointed out in the following 20 description, I will now refer to the drawings, in which Figure 1 is a view in rear elevation of the marker arms, the markers, the supports and including also a sectional view of the lister plow beams and seat beam showing 25 the relation of the marker arms to the implement frame.

Figure 2 is a view in side elevation of a lister with the marker attached thereto, only such parts of the lister being shown as are 30 necessary to disclose the relation of the marker to the lister.

Figure 3 is a plan view of the lister and marker shown in Figure 2.

The lister here shown consists of a front 35 frame and a rear frame which are pivotally connected together, the front frame carrying the lister plows. As shown, the plow beams 10 are parallel and they have secured thereto and between them a more or less U-shaped frame 11. To the transverse portion of the frame member 11 is pivotally secured a bail axle 12 having rear supporting wheels 13. The forward ends of the plow beams 10 are supported on caster wheels 14 as best shown 45 in Figure 2. Extending rearwardly from the forward part of the implement frame is a seat supporting beam 15 which is supported in its rear portion on the rear wheel support by means of one or more supports 16. Forward of the seat 17 is a lever 18 with appro-

priate latching mechanism for elevating and lowering the pivotal point of the members 11 and 12. It is obvious that when this pivot is raised the plow bodies are raised and that the plow bodies may be lowered by manipulating the lever 18 so as to lower the pivot. The seat beam 15 remains substantially stationary throughout these movements because both its front and rear ends are at fixed heights above the surface of the soil. The 55 wheels 13 and 14, however, approach each other when the plows are raised. The lister as above described carries two plow bodies 19. In carrying out the invention a bracket 20 is secured by means of bolts or the like to the seat beam 15. The two arms 21 are each hinged to the bracket 20 by means of longitudinally positioned pins. Each arm carries a marker member 22 of any desired design at its outer extremity. The marker arms 21 are 60 braced by means of forwardly and inwardly extending braces 23 terminating at the forward ends of the plow beams 10.

Since the seat beam 15 is in a more or less fixed position above the surface of the soil, 65 the pivots and therefore the inner ends of the marker arms 21 will be at a constant level above the surface of the soil. The marker arms, however, rest on the plow beams 10 so that every change in the elevation of the plow beams 10 is communicated to the outer ends 70 of the marker arms 21 and therefore to the marker members 22. The movement will, of course, be considerable because of the leverage 75 exerted on the arms 21. It will be obvious from the foregoing description that whenever the plows are raised out of the ground the marker arms will be moved on their pivots until the marker members of the upper ends 80 of the arms will be high enough to clear all 85 obstructions.

Furrows are cut at various depths and provision has been made for appropriate adjustment to take care of these varying depths. For this purpose there is employed a wedge 90 block 24 on each arm 21. The wedge block tapers throughout a portion of its length and it is provided with a plurality of apertures through which bolts may be passed and 95 through the arms 21. These blocks may be 100

moved inwardly to elevate the outer extremities of the arms 21 or outwardly to lower them. They provide a considerable range of adjustment but when this is found to be insufficient, the blocks 24 may be reversed in end to end relation to still further increase the range of adjustment. The device is, however, provided with other adjusting features which materially increase the range of adjustment of the marker arms. In the pivotal connections between the marker arms 21 and the bracket 20 it will be noticed that hinge straps are secured to the marker arms on their lower surfaces so that the hinge pins 15 are in alignment with the lower surfaces of the arms. The hinges are provided with removable pins so that when it is desired to swing the marker members 22 through an arc at a higher level, it is only necessary to turn 20 the marker arms bottom side up and to insert the pivot pins, after which the marker members 22 must also be reversed. Should still further adjustment be needed the wedge blocks may also be employed.

25 When used with a two row lister such as that shown in the drawings, one of the marker members 22 is allowed to ride in the previous furrow so that the other marker member 22 will mark the line of the new furrow. 30 At the end of the furrow the plows and the marker members 22 are raised simultaneously and the implement is turned around to travel in the opposite direction. This, of course, reverses the positions of the two marker members so that the member 22 which formerly served as a guiding member now serves as a marker member.

From the foregoing description it will be apparent that the marker members 22 will be 40 automatically raised or lowered whenever the plows are raised or lowered. It will also be evident that the range of adjustability is considerable either through the structure which permits the turning of the marker 45 arms or through the adjustable wedge block structure 24 or through both.

While I have described and shown the marker in its relation to a specific form of two row lister, I wish it to be understood that 50 the marker arm as above described is applicable to any tillage implement having a frame and the beam of the tillage tool pivotally connected to the frame whereby the tillage tools may be raised or lowered about the 55 pivotal connection.

Having thus described my invention in such full, clear, and exact terms that its construction and operation will be readily understood by others skilled in the art to which 60 it pertains, what I claim as new and desire to secure by Letters Patent of the United States is:

1. A landmarker adapted for use with an earth working implement having a frame 65 and a tool beam pivotally connected thereto

and movable in a vertical plane, said landmarker including a marker arm and a marking member at the outer extremity of said marker arm, and means for pivotally connecting said marker arm at its inner extremity to the implement frame so as to extend over and to rest on the tool beam of the implement frame, the arrangement being such that the movement of the tool beam is communicated to said marker arm.

2. In combination, a tillage implement including an implement frame, a beam pivotally connected thereto, a tillage tool secured to said beam at the free extremity thereof, means for moving said beam on its pivot to raise or lower said tool, and a marker arm pivotally connected at one of its extremities to said implement frame to overlie and to rest on said beam whereby the raising and lowering of said tillage tool causes the raising and lowering of the free extremity of said marker arm.

3. A landmarker adapted for use with a tillage implement having an implement frame and a tillage tool beam pivotally connected thereto and having means for raising and lowering the tillage tool about the pivotal connection of the tool beam, said landmarker including an arm adapted to be pivotally connected at one of its extremities to the implement frame to overlie and to rest on the tool beam and to project to one side of the implement frame, and means for adjustably spacing said marker arm from the tool beam.

4. A landmarker adapted for attachment to a soil tillage implement having a beam supported tillage tool, the beam being pivotally secured to the implement frame and being movable on its pivotal connection to raise and lower the tillage tool, said landmarker including an arm adapted to be pivotally secured to a fixed portion of the implement frame in a manner so as to overlie and to be supported by the beam of the tillage tool whereby the raising or lowering of the tillage tool causes the raising or lowering of the free extremity of said arm, and a wedge block secured to the under side of said arm, said wedge block being adjustable in the direction of the length of said arm.

5. A pair of landmarker arms adapted to be secured in alignment transversely of a two row lister having an implement frame with a fixed member intermediate its sides and having lister plow beams pivotally connected to the implement frame on opposite sides of the fixed member, the plow beams being adapted to be raised and lowered, said landmarker arms being each pivotally secured to the fixed member intermediate the sides of the implement frame so as to overlie and be supported by the plow beams whereby said landmarker arms are automatically raised or lowered when the plows are raised

or lowered, and landmarking members secured to said landmarker arms at the outer extremities thereof.

6. A landmarker adapted for attachment to a soil tillage implement having a beam supported tillage tool, the beam being pivotally secured to the implement frame and being movable on its pivotal connection to raise and lower the tillage tool, said landmarker including a marker arm, a hinge strap secured to said marker arm on one surface thereof, a hinge member adapted to be secured to a fixed portion of the implement frame, a releasable pin connecting said hinge member and said hinge strap in either of two positions, the arrangement being such that said arm will overlie and will be supported by the beam of the tillage tool whereby the raising or lowering of the tillage tool will cause the raising or lowering of the free extremity of said marker arm.

In testimony whereof I affix my signature.
LEON W. CHASE.
